[57] **ABSTRACT**

A device is provided for setting pivotally mounted jacks in a pattern wheel. Such device includes a means for rotatably supporting the jack retaining ring of the wheel, mechanism for indexing such ring by rotating the ring to successively align jacks with a selectively operable jack raising lever, and camming means for flipping over raised jacks as the indexing mechanism rotates the jack-supporting ring.

DEVICE FOR SETTING PIVOTALLY MOUNTED JACKS IN A PATTERN WHEEL

BACKGROUND OF THE INVENTION

1. Field of the Invention

The invention relates to pattern wheels for circular knitting machines and more particularly to mechanisms for setting jacks in such wheels.

2. Description of the Prior Art

It is known in the art to provide a pattern wheel with radially slideable jacks, and mechanism as shown, for example, in U.S. Pat. No. 2,990,702 is available for use in setting such jacks in the wheel. However, it is difficult and costly to manufacture a pattern wheel as shown in the said patent, and such pattern wheel is inefficient in operation. A principle difficulty is that the jacks in such a pattern wheel may not be swedged at their outer ends for engagement with needle butts since the swedged ends would prevent radial movement of the jacks in pattern wheel slots. The jacks must be uniform in thickness throughout their length and their thickness must be greater than would be required if the ends which contact the needle butts could be swedged. The walls of the pattern wheel defining slots for the jacks must therefore be thin and inserts are required to form the walls because of the otherwise difficult if not impossible machining problem presented. Also, since the walls cannot be tapered at their outer extremities to provide gear-like teeth to mesh with the butts of needles, freedom from interference between needle butts and the walls of the pattern wheel cannot be assured. There is therefore a need for a pattern wheel from which the aforesaid disadvantages have been eliminated and for a device which may be used to set the jacks in such wheel. Our copending Patent Application for "Pattern Wheel with Pivottally Mounted Jacks," Ser. No. 27,014 filed Apr. 9, 1970, (Now U.S. Pat. No. 3,620,049) is directed to such a wheel and the present application is directed to a device for setting the jacks in the wheel.

SUMMARY OF THE INVENTION

The jack setting device of the invention includes means for rotatably mounting the jack-supporting ring of a pattern wheel, means selectively operable on the jacks for raising jacks from a needle actuating position and cam means engageable with the raised jacks for flipping over such jacks to a non-actuating position upon relative motion of the jack-supporting ring and cam means.

It is an object of the invention to provide an improved jack setting device operable to index the jack-supporting ring of a pattern wheel and to move pivotally mounted jacks therein from a needle actuating to a non-actuating position.

It is another object of the invention to provide a jack setting device which is effective to move a pivotally mounted jack in the jack-supporting ring of a pattern wheel into a non-actuating position while the ring is indexed for jack-selection.

It is still another object of the invention to provide a device for setting jacks in pattern wheels which is simple in construction and both reliable and efficient in operation.

Other objects and advantages of the invention will become apparent during a reading of the specification taken in conjunction with the accompanying drawings.

DESCRIPTION OF THE DRAWINGS

FIG. 1 is a perspective view showing a jack-setting device according to the invention;

FIG. 2 is a fragmentary diagrammatic perspective view showing the manner in which jacks are set by the device of the invention;

FIG. 3 is a fragmentary vertical sectional view taken on the plane of the line 3—3 of FIG. 1;

FIG. 4 is a fragmentary perspective view showing portions of the device of FIG. 1;

FIG. 5 is a vertical sectional view taken on the plane of the line 5—5 of FIG. 1; and

FIG. 6 is a vertical sectional view taken on the plane of the line 6—6 of FIG. 1.

DESCRIPTION OF THE PREFERRED EMBODIMENT

Referring to the drawings, reference character 10 designates the jack-supporting ring of a pattern wheel of the kind shown and described in our copending application for "Pattern Wheel with Pivottally Mounted Jacks," Ser. No. 27,014 filed Apr. 9, 1970.

The supporting ring includes jacks 12 pivotally mounted on arms 14 which are held in the ring with finger 16 in annular slot 18 and cover 20 secured to the ring, by screws 22, the jacks being movable between needle-actuating positions wherein outer portions extend into spaces 24 between teeth 26 of the supporting ring 10 and non-actuating or folded positions wherein the jacks rest on the top of the arms 14.

15 The device of the invention for use in setting jacks in a pattern wheel is denoted by reference character 28 and includes a base 30 and a handle 32, to which a plate 33 is secured at 34. A shaft 36 fixedly mounted in the handle 32 rotatably supports the handle in the base. Slot 38 in plate 33 and slot 40 in the handle receive respectively a stub shaft 42 and an integral foot 44 located at one end of the shaft. The other end of the shaft 42 is threaded at 46 to receive a nut 48 for securing the stub shaft 42 and a sleeve 50 thereon in a fixed position on the handle 32 with the axes of the stub shaft 42 and sleeve 50 coincident with or eccentric to the axis of shaft 36, and with hub 51 which is fixedly associated with the pattern wheel jack-supporting ring 10 rotatable on the sleeve 50. The position of the axis of rotation of the ring 10 with respect to the axis of rotation of the handle 32 is determined according to the position selected for the stub shaft 42 in slot 40. The purpose of having the relative positions of such axes subject to variation is to enable the device of the invention to accommodate within limits pattern wheel jack-supporting rings of different size.

35 The handle 32 includes an angular slot 52 and a lifting lever 54 which is pivotally mounted at 56 in the slot 52. Lever 54 is flanged at one end to form a pad 58 and is provided at the other end with a jack engageable finger-like portion 60. A spring 62 urges the lever 54 to a position wherein the pad 58 is above the handle and finger-like portion 60 is below the jack retaining ring 10. A pawl 64 is pivotally mounted at 66 on a member 68 which is secured to the handle at 70 and such pawl is biased by spring 72 into engagement with the pattern wheel supporting ring 10. The relative locations on the handle 32 of member 68 and slot 52 are such that with the pawl 64 in a space 24 between teeth 26 on the supporting ring 10, depression of the lever 54 at pad 58 will result in the finger-like portion 60 of the lever entering a space 24 between the teeth 26 of the supporting ring.

50 The handle 32 is movable in a clockwise direction, as viewed in the drawings, from a rest position wherein the handle engages a stop 74 to a position wherein the handle is engaged by another stop 76, and during such clockwise rotational movement the pattern wheel jack-supporting ring is moved with the handle 32 by pawl 64. Release of the handle 32 at the stop 76 results in the handle being returned to the rest position by a rod 78 slidably mounted in the base 30 and biased by spring 80 against the handle 32. During such return movement of the handle, the jack-supporting ring remains stationary, as will be explained hereinafter.

55 When operating the device to set jacks, successive clockwise rotational movements are imparted to the handle 32 and ring 10. Prior to the initiation of any such movement of the handle the lever 54 may be depressed at pad 58, that is, moved from position A to position B, to raise a jack 12 from the needle actuating position in which all jacks are initially disposed, or the lever may be left in the position in which it is biased by spring 62. If it is decided that a jack in alignment with the lever 54 is to be set in a non-actuating position the handle is depressed prior to the handle being rotated. If however, the jack is to remain in a needle actuating position the lever 54 is not depressed prior to rotation of the handle.

70 Assuming the lever 54 is depressed and the handle 32 then rotated, the jack 12 with which the lever 54 is aligned is raised about its pivotal mounting by the finger-like projection 60 on

the lever. Then as the handle 32 is rotated, the pawl 64 pushes on the pattern wheel supporting ring 10 and the ring turns causing the jack to come in contact with contoured surface 81 of the cam 82 which is secured to the base 30 at 84 and 86. When the lever 54 is depressed at the rest position of the handle 32, a lever 88 pivotally mounted on the handle at 90 is caused by spring 92, which is secured to the handle at 94, to assume a position wherein a finger 96 at one end overlies the lever 54 to hold it in the depressed condition. The lever 54 is released when the handle in its clockwise motion reaches a point at which stop 98, adjustably mounted on the base at 100, contacts the lever 88 causing such lever to pivot so that the finger 96 is withdrawn from its position over the lever 54, whereupon spring 62 moves the lever 54 to position C wherein the pad 58 is once again a substantial distance above the handle. The adjusted position of the stop should be such that release of the lever 54 occurs just prior to the handle 32 obtaining its limiting position in its clockwise motion as defined by the engagement of the handle with stop 76. As previously indicated, when the handle 54 is released at the stop 76 the handle is returned to its rest position by rod 78 under the influence of spring 80. During the return movement of the handle, the jack-supporting ring 10 remains stationary and the raised jack remains on the cam 82, reverse rotational movement of the jack-supporting ring being prevented by pawl 102 mounted at 104 in member 106 which is secured at 108 to the base 30. Subsequent clockwise rotational movements of the handle 32 and ring 10 result in the raised jack 12 being flipped over to a non-actuating position by surface 81 on the cam 82.

When the handle returns to the rest position, lever 54 comes into alignment with another jack in the jack-supporting ring and such jack may be raised for actuation by cam 82 as described or not according to the position desired for the newly aligned jack in the wheel. If the lever 54 is not depressed, the jack in alignment with the lever 54 remains in the needle actuating position when the handle 32 and jack-supporting ring are turned, and it is never brought into contact with the cam 82. Although in FIG. 1 some jacks and associated arms 14 have been omitted to simplify the drawing, it is to be understood that ordinarily the ring would be filled with jacks, no accommodating slot being left vacant.

The stops 74 and 76 are adjustable by screws 110 and 112 respectively which may be set so that rotational clockwise movement of the handle and its accompanying counter-clockwise return movement results in aligning the lever 54 with each of the jacks in the ring successively such that all of the jacks are rendered available for selection, or the stops may be set so that only some of the jacks, as for example, every other jack, on the ring is brought into alignment with lever 54.

After the jack-supporting ring has been completely rotated in the device 28 and positions determined for the jacks in the

manner described, the jack-supporting ring 10 with its attached cover is removed from the device. A final cover as shown in the aforementioned patent application Ser. No. 27,014 may then be applied over the jacks to assure that the jacks are held in the positions determined for them by operation of the device 28.

While the invention has been described in its preferred form, it is to be understood that the words which have been used are words of description rather than of limitation, and 10 that changes within the purview of the appended claims may be made without departing from the true scope and spirit of the invention.

Having thus set forth the nature of this invention, what is claimed herein is:

15. A jack setting device for a needle controlling pattern wheel which includes a jack-supporting ring and jacks pivotally mounted in the ring for movement between a needle-actuating and a non-actuating position, said device comprising a support for the ring, and jack actuating means selectively operable on the jacks for moving jacks on their pivotal mountings between the needle-actuating and non-actuating position, the ring and jack actuating means being relatively rotatable whereby jacks may be successively disposed for actuation by the jack actuating means, said jack actuating means including means operable to raise jacks from the needle-actuating position, and cam means engageable with the raised jacks for flipping over the raised jacks to the non-actuating position upon relative rotation of the jack-supporting ring and cam means.
20. 2. A device as defined in claim 1 wherein the ring and jack actuating means have axes of rotation which are relatively adjustable.
25. 3. A device as defined in claim 1 wherein the jack-supporting ring is at times rotatable with the jack raising means and the jack raising means is at other times rotatable with respect to the ring.
30. 4. A device as defined in claim 3 wherein the cam means is affixed to the support for the wheel.
35. 5. A device as defined in claim 3 including means for restricting rotation of the wheel to one direction.
40. 6. A device as defined in claim 5 including means defining limits of rotational movement for the jack raising means.
45. 7. A device as defined in claim 6 wherein said means defining limits of rotation are adjustable.
50. 8. A device as defined in claim 6 including spring means for moving the jack raising means with respect to the wheel.
9. A device as defined in claim 6 including means for locking the jack raising means in an operated position and for unlocking the jack raising means at the end of a defined rotational movement.
